UNITED STATES PATENT OFFICE.

CORNELIUS B. DICKERSON, OF POWHATAN, WEST VIRGINIA.

SUSPENDER-HOOK AND DRAWERS-SUPPORT.

No. 884,906.

Specification of Letters Patent. Patented April 14, 1908.

Application filed August 21, 1907. Serial No. 389,594.

To all whom it may concern:

Be it known that I, CORNELIUS B. DICKERSON, a citizen of the United States, residing at Powhatan, in the county of McDowell 5 and State of West Virginia, have invented a new and useful Suspender-Hook and Drawers-Support Combined, of which the following is a specification.

This invention relates to garment supporters and its object is to provide a simple, durable, and efficient device of this character 10 designed to be secured to trousers and having integral but separate means for engaging suspenders and drawers whereby the same 15 may be held in proper relation to one another without causing discomfort to the wearer.

A still further object is to provide a device of this character which is formed in a single piece of metal, which can be manufactured 20 cheaply, and which can be readily attached to or detached from the suspenders or drawers with which it is used.

With these and other objects in view the invention consists of certain novel features 25 of construction and combinations of parts which will be hereinafter more fully described and pointed out in the claims.

In the accompanying drawings is shown the preferred form of the invention.

30 In said drawings: Figure 1 is an elevation of the supporter, the same being shown in use. Fig. 2 is a detail view of the blank from which the supporter is formed. Fig. 3 is a longitudinal section through the supporter and showing the supplemental strap used in connection therewith for attaching it to trousers.

Referring to the figures by characters of reference, 1 designates an elongated metal 40 strip provided adjacent its center with oppositely extending ears 4 each of which is provided with an aperture 5 so that the same can be conveniently sewed to a garment. Elongated parallel slots 6 are formed within 45 the strip between these ears and a transverse bar 7 is thus produced for the purposes hereinafter set forth. Ears 3 extend laterally from the base portion 2 of the strip 1 and each of them is provided with openings 5 for 50 the reception of stitches and located between these ears 3 and integral with the strip 1 is a hook 9 which overhangs the adjoining portion of the strip 1 and is channeled in the direction of its length as indicated in Figs. 2 55 and 3 so that the same is reinforced and presents a rounded lower surface designed to

bear within the strap 14 of a pair of suspenders.

The end portion 16 of the strip 1 extends from the bar 7 in a direction opposite to the 60 end portion 2 and is designed to be folded as indicated at 10 so as to extend substantially parallel with the base portion 2 of the strip 1. This end portion 16 constitutes a tongue, the 65 longitudinal edges of which are curved as indicated at 11 and 12 and merge to form a rounded end which is struck inwardly to form a depression 13 into which the end of hook 9 is designed to project.

In using the device herein described the 70 base portion 2 is secured to the waist band of trousers by sewing through the openings 5 and if desired it may be additionally fastened thereto by extending a fabric tape 8 through the slots 6 and around bar 7 as indicated at 75 3, the ends of said tape being sewed to the trousers. The tongue 16 may then be placed in engagement with the supporting strap 15 of drawers simply by placing said strap back of the terminal of tongue 16 and on the hook 80 9 whereupon the tongue 16 will spring away from hook 9 and permit the strap to assume a position within the fold 10. The strap 14 of suspenders can then be similarly placed in engagement with the hook 9 whereupon the 85 parts will be assembled as indicated in Fig. 1. Should it be desired to detach the suspender strap from hook 9 the same is swung laterally into position substantially at right angles to the tongue 16 and then pressed downward 90 so that the upper portion of the eye in the strap will slip down off of hook 9 and between the base portion 2 and the tongue 16. The strap will thus become detached. To disconnect the strap 15 from the supporter 95 one end thereof is pulled upward over the hook 9 and then pulled downward between it and the end of tongue 16 whereupon said strap will likewise be disconnected.

It will be seen that this supporter is very 100 simple, durable, and efficient, can be readily placed in position, and when once secured does not require the use of separate pieces for securing or releasing the parts engaged thereby. It is formed in a single piece of 105 spring metal and inasmuch as it can be produced at a single operation it will be apparent that the same can be manufactured at extremely small cost.

What is claimed is:

A garment supporter formed in a single piece of spring metal and comprising a base

having laterally extending ears for the reception of securing means, said base having parallel slots forming a transverse bar, a hook at one end of the base and lapping the same, 5 said hook being concavo-convex in transverse section, a tongue extending through one end of the base and lapping the hook, said lapping portion of the tongue having a circular concavity, and an elastic strip extending through the slots and looped around 10

the bar, the terminals of said strip being disposed to be fastened to a garment.

In testimony that I claim the foregoing as my own I have hereto affixed my signature in the presence of two witnesses.

CORNELIUS B. DICKERSON.
